UNITED STATES PATENT OFFICE.

ROBERT DELAUNAY-BELLEVILLE, OF ST.-DENIS, FRANCE, ASSIGNEE TO SOCIETE ANONYME DES AUTOMOBILES DELAUNAY-BELLEVILLE, OF ST.-DENIS, FRANCE, A CORPORATION OF FRANCE.

CARBURETER.

1,130,490.

Specification of Letters Patent. Patented Mar. 2, 1915.

Application filed March 31, 1913. Serial No. 753,608.

To all whom it may concern:

Be it known that I, ROBERT DELAUNAY-BELLEVILLE, citizen of the French Republic, residing at St.-Denis, Department of the Seine, in France, have invented certain new and useful Improvements in and Relating to Carbureters for Internal-Combustion Engines; and I do hereby declare the following to be full, clear, and exact description 10 of the invention, such as will enable others skilled in the art to which it appertains to make and use the same.

The invention relates to carbureters, and has for its object to provide a carbureter in which the supply of fuel will be automatically controlled to insure a mixture of air and fuel in a constant proportion whatever the speed of the engine may be.

The invention consists in providing two sets of nozzles one of which discharges in the direction of the suction air current and the other discharges in the direction opposite to said current. It is evident that the discharge from the nozzles in the latter case is retarded by the action of the air current and the higher the vacuum the greater the velocity, and consequently the greater the degree of retardation will be while the discharge of the nozzles in the direction of the suction air current increases, as usual, with the vacuum.

In the accompanying drawing: Figure 1 shows, by way of example, a section through a carbureter provided with a device for controlling the fuel according to the invention. Fig. 2 shows a modification thereof. Fig. 3 shows one form of the upper end of the nozzles. Fig. 4 is a section on line A—A of Fig. 3.

In Fig. 1 it is assumed that one nozzle only is used and which is provided with two orifices; one discharging in the direction of the air current and the other in the opposite direction. The tube 1 supplied with fuel from the constant level reservoir 2, discharges into the suction pipe 3 connected to the cylinders of the engine. The suction pipe 3 has a conical restriction 4 intended to increase the velocity of the air current in the vicinity of the fuel supplying tube 1; said pipe being further provided with a butterfly valve 5 or any other gas throttling device, above the tube 1. This nozzle, is bent at its upper end in such a

manner that a branch 6 turns downwardly and parallel to the tube 1. This branch is provided, at its end, with an orifice 7 of suitable diameter, the bend being also provided, at its highest point with an orifice 8.

The operation of the device is as follows: Owing to the suction, the fuel rises in the bend of the tube flows through the orifices 7 and 8. The output of the orifice 7 of the nozzle diminishes in proportion as the vacuum increases because the jet of liquid leaving by this orifice is retarded on leaving by the ascending air current and the degree of retardation is greater the higher the degree of vacuum and consequently the greater the velocity of the air. The upper orifice 8 discharges, on the contrary a larger quantity of fuel as the vacuum increases, as in the case of ordinary nozzles. It will be evident that the orifice 7 produces a rich mixture when the engine is running at low speed and the opposite result will be produced by the orifice 8. It may happen that the air velocity may become so great that no fuel will leave through the lower orifice 7, in this case air will enter the branch 6 and will escape together with the fuel, through the orifice 8.

It is evident that by appropriately adjusting the orifices 7 and 8 and their relative positions with regard to the fuel level and to the restriction in the suction pipe, it is possible to obtain a compensating effect which will maintain the composition of the mixture constant whatever the speed of the engine may be.

In Fig. 1, the orifices 7 and 8 are situated at different levels; if it is desired to place them on the same level then the arrangement shown in Fig. 2 is used. In this form, two nozzles are employed, one being shown at 1' and having a fuel delivery orifice at 8', from which fuel is delivered in the direction of the air current, and a second nozzle shown at 1'' having a fuel delivery orifice 7' to deliver the fuel in an opposite direction to the air current. It will be understood that in the form shown in both Figs. 1 and 2, the fuel delivery orifices should be situated above the normal fuel level.

In a general manner, any number of orifices may be directed downwardly, a nozzle according to Figs. 3 and 4 is then used which is provided with a certain number of passages 7'' directed downwardly and only

one upper orifice 8" in the axis of the nozzle. In this manner a nozzle is obtained which is simple in construction, easy to dismantle and can be very easily controlled in 5 most cases.

The upwardly directed orifice of a single nozzle can be multiplied and even multiple nozzles can be used.

I claim:

10. 1. A carbureter comprising an air conduit and fuel injecting means having a fuel delivery orifice to direct a jet of fuel in said conduit in the same direction as the air passing through said conduit, and a fuel 15 delivery orifice to direct a jet of fuel in an opposite direction to the air passing through the conduit.
20. 2. A carbureter comprising an air conduit and fuel injecting means associated with said conduit, said injecting means comprising a nozzle adapted to direct a jet of fuel in the same direction as the current of air passing through said conduit, and a second nozzle adapted to direct a second jet of 25 fuel in an opposite direction to said current of air.

3. A carbureter comprising an air conduit, a fuel injecting nozzle adapted to direct a jet of fuel in the same direction as the current of air passing through said conduit, and a second nozzle adapted to direct a second jet of fuel in the opposite direction to the air current, said second nozzle adapted to permit the air in said conduit to retard the discharge of fuel therefrom. 30

4. A carbureter comprising an air conduit and fuel delivery means having one fuel delivery orifice so disposed that its supply of fuel increases as the velocity of air in said conduit increases, and a second fuel 40 delivery orifice the supply of fuel from which decreases as the velocity of air in said conduit increases, such decrease being due solely to the disposition of said second orifice. 45

In testimony whereof I affix my signature, in presence of two witnesses.

ROBERT DELAUNAY-BELLEVILLE.
